UNITED STATES PATENT OFFICE

159,704

UTILITY BOX OR THE LIKE

Joseph R. Watkins, Dover, N. J., assignor to Foster Grant Co., Inc., Leominster, Mass., a corporation of Massachusetts

Application December 21, 1949, Serial No. 6,754

Term of patent 3½ years

(Cl. D86—10)

To all whom it may concern:

Be it known that I, Joseph R. Watkins, a citizen of the United States, residing at Dover, Morris County, State of New Jersey, have invented a new, original, and ornamental Design for a Utility Box or the like, of which the following is a specification, reference being had to the accompanying drawing, forming part thereof, in which:

Fig. 1 is a top plan view of a utility box or the like, showing my new design; and

Fig. 2 is a side view of the cover removed from the box, the box being shown in dot and dash lines.

The characteristic features of the design are shown in full lines.

I claim:

The ornamental design for a utility box or the like, substantially as shown and described.

JOSEPH R. WATKINS.
